UNITED STATES PATENT OFFICE.

WILLIAM A. LINDSAY, OF WILMINGTON, DELAWARE.

PAPER-MAKING MACHINE.

SPECIFICATION forming part of Letters Patent No. 340,335, dated April 20, 1886.

Application filed February 23, 1886. Serial No. 192,857. (No model.)

To all whom it may concern:

Be it known that I, WILLIAM A. LINDSAY, a citizen of the United States, residing in Wilmington, Delaware, have invented certain

5 Improvements in Paper-Making Machines, of which the following is a specification.

My invention relates to that part of the machine in which the paper web is dried by passing it around heated cylinders, one object of 10 my invention being to effect the drying of the paper more rapidly and uniformly than is possible in machines as at present constructed, and a further object being to provide a drier-apron of a more durable character than those 15 now in use.

In the accompanying drawings, Figure 1 is a diagram illustrating sufficient of a paper-making machine to represent my invention; Fig. 2, a view showing one of the features of 20 the invention, and Figs. 3 and 4 diagrams illustrating modifications of the invention.

25 A A', A², &c., represent the successive drying-cylinders of the machine, which may be the usual hollow steam-heated cylinders, or may be constructed in any other desirable manner; and a are the rolls which serve to direct the web of paper, the latter entering the drier in the direction of the arrow from the second press-rolls, and passing from the drier 30 to the calender-rolls.

The web of paper is in contact with each of the drying-cylinders throughout the greater portion of the circumference of each cylinder, and said web is held in intimate contact with 35 the cylinders by means of the drier-apron B, which passes part way round each cylinder, round directing-rollers b, and round stretching-rollers d, by the adjustment of which the apron is maintained under proper tension.

40 All these parts are arranged in the usual manner; but in the machine as at present constructed the drier-apron consists of a web of cotton cloth or canvas; or, in rare instances, a woolen felt is employed. In either case,

45 however, the web soon becomes so condensed as to be practically impervious to and incapable of absorbing moisture, the result being that there is no driving off of moisture from the web of paper while it is confined between 50 the drier-apron and the heated cylinder, the drying of the paper web being effected while

it is exposed to the atmosphere in passing from one cylinder to another—for instance, between points x x, Fig. 1.

I have found that it is possible to use, in 55 place of the usual drier apron or web of textile fabric, an apron of wire-gauze or perforated metal, the gauze being of such fine mesh that it will not injuriously indent the moist web of paper, and being composed of brass, copper, 60 bronze, or other metal which will not become rusted, or, if composed of oxidizable metal, being galvanized or electroplated to prevent rust. A drier-apron of this character, while confining the web of paper snugly to the drying- 65 cylinders, affords, as will be evident, a ready chance for the escape of moisture from that portion of the web which is in contact with the drying-cylinder, and therefore insures the drying of the web much more rapidly and 70 uniformly than is possible when the usual textile drier-felt is employed. The wire-gauze drier-apron, moreover, is practically indestructible, whereas the usual textile apron is rapidly destroyed by the continuous wetting 75 and drying to which it is subjected.

In order to provide the opposite ends of the wire-gauze strips with loops, whereby said ends may be properly laced together, I interweave with the gauze, at and near each end, 80 a wire, w, this wire forming projecting loops for the reception of the lacing-wire m, as shown in Fig. 2, the extent of projection of the wire w into the gauze strip being differential, so that the strain will be distributed over a large 85 area of the strip.

As shown in Fig. 2, the lacing-loops at one end of the strip alternate with those at the other end; but the loops may, if desired, be arranged opposite to each other, as shown in 90 Fig. 3, and may be laced together, as shown in said figure; or the loops may be connected by means of a transverse rod, n, in the nature of a hinge-pintle, as shown in Fig. 4.

I claim as my invention—

1. The combination of the drying-cylinders of a paper-making machine with a drier-apron consisting of wire-gauze or perforated sheet metal, all substantially as specified.

2. A drier-apron for paper-making machines, consisting of a wire-gauze strip, with each end of which is interwoven a wire form-

ing a series of projecting loops for the reception of a lacing-wire, all substantially as set forth.

3. The combination of the wire-gauze strip, 5 forming the drier-apron, with the lacing-loop wire *w*, the extent of projection of which into the strip is differential, all substantially as and for the purpose set forth.

In testimony whereof I have signed my name to this specification in the presence of two subscribing witnesses.

WILLIAM A. LINDSAY.
